US0D1050811S

(12) **United States Design Patent** (10) **Patent No.:** **US D1,050,811 S**
(45) **Date of Patent:** ** *Nov. 12, 2024

(54) **CUP WITH LID SET**

(71) Applicant: **Clarity, Inc.**, Los Angeles, CA (US)

(72) Inventor: **Glenn Tobias**, Los Angeles, CA (US)

(73) Assignee: **Clarity, Inc.**, Los Angeles, CA (US)

(*) Notice: This patent is subject to a terminal disclaimer.

(**) Term: **15 Years**

(21) Appl. No.: **29/722,104**

(22) Filed: **Jan. 27, 2020**

Related U.S. Application Data

(62) Division of application No. 29/650,511, filed on Jun. 7, 2018, now Pat. No. Des. 873,613.

CLAIM

The ornamental design for a cup with lid set as shown and described.

DESCRIPTION

FIG. 1 is a perspective view of a cup with lid set, shown in an open position, showing our new design;

FIG. 2 is a top view thereof, shown in an open position;

FIG. 3 is a bottom view thereof, shown in an open position;

FIG. 4 is a right side view thereof, shown in an open position;

FIG. 5 is a left side view thereof, shown in an open position; and,

FIG. 6 is a perspective view thereof.

The broken lines in the drawings depict portions of the cup with lid set, that form no part of the claimed design.

1 Claim, 6 Drawing Sheets
